(Cl. D14—3)

FIG. 4

Fig. 1 is a side elevational view, showing a tractor embodying our new design;

Fig. 2 is a top plan view;

Fig. 3 is a front elevational view, the rear of the tractor being conventional; and

Fig. 4 is a view in perspective of the tractor, taken from the side opposite that shown in Fig. 1, from the front end, and from above.

The essential features of our design reside in those portions shown in full lines.

We claim:

The ornamental design for a tractor, as shown and described.
